UNITED STATES PATENT OFFICE.

SETH D. TRIPP, OF LYNN, MASSACHUSETTS.

WRAPPING-MACHINE.

SPECIFICATION forming part of Letters Patent No. 472,202, dated April 5, 1892.

Application filed July 1, 1891. Serial No. 398,126. (No model.)

To all whom it may concern:

Be it known that I, SETH D. TRIPP, of Lynn, county of Essex, State of Massachusetts, have invented an Improvement in Wrapping-Machines, of which the following description, in connection with the accompanying drawings, is a specification, like letters on the drawings representing like parts.

This invention has for its object to construct a machine for wrapping oranges and similar spherical objects.

In accordance with this invention a suitable feeding-device is employed for feeding the oranges one at a time to a folder and twister, and a suitable centering device is provided for properly directing the orange or article to be wrapped. The folder and twister is herein represented as an intermittently-rotatable ring carrying a series of automatically-movable arms formed or provided at their lower ends with wings or equivalents which co-operate with each other to constitute nipping devices. The paper is taken from a roll and by suitable feeding mechanism is fed forward and cut off, the severed sheets of proper sizes being laid over or upon the combined folder and twister, and suitable means are provided for guiding the paper properly regardless of its width. The orange or other article to be wrapped is forced by a suitable plunger down through the centering device, falling upon the sheet of paper which is laid upon the folder and twister, and continuing its descent, assisted by said plunger, it passes down into and through the said folder and twister, carrying the paper with it, until the edges of the paper are caught and held by the nipping devices, the wrapper being then gathered in just above the article. A holder of suitable construction is provided, which, is herein shown, is designed to engage the gathered-in portion of the paper or wrapper next the orange or article while the edges are yet held by the folder or twister, and the latter being at such times rotated the gathered-in portion or edges of the paper will be twisted while the orange is restrained from rotation. This holder is also employed to remove the wrapped orange from engagement with the combined folder and twister and, as shown, is arranged to operate while the combined folder or twister is operating, so that the gath-

ered-in portion of the wrapper will be twisted from a point next the orange to the extreme edges of the wrapper. A suitable printing device is employed, made adjustable with relation to the other parts, to print the name or any other inscription upon the wrapper.

Figure 1 shows in side elevation a machine for wrapping spherical objects embodying this invention; Fig. 2, a front elevation of the machine shown in Fig. 1; Fig. 3, a cross-sectional view of the machine shown in Fig. 1, taken on the dotted line $x-x$; Fig. 4, a top view of a portion of the feeding device; Fig. 4^a, a front view of a portion of the feeding device, showing the plunger or pendant; Fig. 4^b, a side view of a portion of the feeding device, showing the plunger or pendant; Fig. 4^c, a detail of the actuating-pawl for the feed-wheel; Figs. 5 and 6, enlarged details of the nipping device for engaging and feeding the paper; Fig. 7, a plan view of the centering device; Fig. 8, a sectional detail of a portion of the centering device; Fig. 9, a detail showing the forked end of the holder; Fig. 10, a detail showing in plan view the nipping devices of the combined folder and twister; Figs. 11 to 14, inclusive, enlarged details of the printing device; Fig. 15, an enlarged detail of the foot and part carrying it, and Fig. 16, a detail showing the stationary blade of the cutting-off mechanism and spring connected to it.

The base or stand A supports a column or vertical cylinder b , which, together with table c , resting on it, constitutes the frame-work which supports the operative and other parts of the machine.

To the under side of table c are secured curved arms d and d' , arranged opposite to each other and bearing at their outer end rolls e , e' . Another roll f revolves upon a pin in a lug projecting from the cylinder b . These rolls are provided with V-shaped peripheral grooves, which afford a guideway for a ring g , having its periphery shaped to fit said grooves. These rolls e , e' , and f are employed mainly as friction-rolls, and hence it is obvious that they may be omitted and the ring made to revolve in stationary grooved bearings.

Secured to the under side of the ring g or made in part with it is a bevel-gear h , which is engaged by a gear h' , fixed upon a shaft i ,

which revolves in a suitable bearing, as j , herein shown as arranged on the arm d' . This shaft i is also provided with another bearing k , formed upon the end of an arm l , the opposite end of which arm is secured to the under side of table c . The shaft i is also provided with a pulley m , by which rotary motion may be communicated to the ring g through the bevel-gears $h' h$.

10 In the circular opening in the ring g are shown four bearing-blocks $n n' n^2 n^3$, located equal distances apart, to which are pivoted upon pins $o o' o^2 o^3$ downwardly and inwardly extended arms $p p' p^2 p^3$, the lower ends of 15 said arms nearly meeting on the line of the axis of the ring. Across the lower ends of each of these arms and in parallelism with the pins upon which they swing are secured plates or wings $y^5 y^6 y^7 y^8$, which consist of 20 narrow flat plates whose length is about equal to the diameter of the opening in the ring g . When the arms are swung outward or away from each other, the inner edges of the plates will form the four sides of a square. (See Fig. 25 10.) The arms $p p^2$, which are diametrically opposite each other are longer and hence project slightly below the ends of arms $p' p^3$, and the wings on said arms $p p^2$ will occupy a plane below the wings on the arms $p' p^3$; but for the 30 purposes to be hereinafter described it is necessary that these wings continuously contact with each other, and hence in order that they may so contact and that the arms carrying them may move on pivots two of the wings 35 will be arranged obliquely to the other two. As shown in Fig. 1, the wings $y^5 y^7$ are oblique and the wings $y^6 y^8$ horizontal, the arms being contracted or drawn toward each other; but when said arms are swung outward or 40 from each other the wings $y^6 y^8$ will be oblique and the wings $y^5 y^7$ horizontal.

Auxiliary arms $c^2 c^3 c^4 c^5$ without wings may be provided to operate in conjunction with those already described, such arms being likewise pivoted to bearing-blocks on the disk g 45 and arranged alternately with relation to the arms $p p' p^2 p^3$. The free ends of the arms $p p' p^2 p^3$ and $c^2 c^3 c^4 c^5$ may be pressed inward by an elastic band r , (see Fig. 3) encircling them 50 all, or each may be pressed in by a spring, as shown in Fig. 8. When an elastic band is used, it is applied from the underside. This device constitutes a combined paper folder and twister operating to fold the paper about 55 the fruit as it passes therethrough and to thereafter twist the paper after the fruit has passed therethrough and during the time that the folded margin of the paper is held by the wings $y^5 y^6 y^7 y^8$. These wings $y^5 y^6 y^7 y^8$ 60 constitute nipping devices to nip the margin of the paper while twisting it.

Pivoted to the lever a^4 is a hook a^2 , which extends vertically, or nearly so, and moves freely in guide-slots in rigid arms $a' a^3$. As the 65 end of the lever a^4 is raised nearly to its most elevated position an arm c^6 , rigidly connected to said hook at right angles with relation

thereto, will come in contact with a lug b^2 on the column b , causing the said hook to assume the position indicated by dotted lines $b^3 b^3$. 70 The upper end of the hook a^2 is forked, (see Fig. 9,) so as to pass astride the folded paper between the fruit and the nipping devices $y^5 y^6 y^7 y^8$, which hold said paper by its edges. As the lever a^4 is moved downward the hook 75 a^2 will carry the fruit down with it, the paper being removed from its engagement with the wings. During the time that the paper is being removed or drawn down by the forked hook a^2 the said hook will act to hold the fruit firmly, so that it cannot be revolved, and the ring g and its arms, revolving during such time, 80 will act to twist the paper. This hook, operating as described, I herein term a "holder." When the downward movement of the hook 85 has drawn the paper entirely out of the nipping devices of the combined folder and twister, the wrapped fruit will fall upon the inclined guide x^4 and will roll away from the machine. As the hook continues to move 90 downward the arm c^6 will come in contact with a lug b^4 on the base, causing the hook to assume the full-line position shown in Fig. 1, so that it may be again moved upward without coming in contact with the suspended fruit. 95

The combined folder and twister is made to revolve intermittently and at the proper time by the following means: The pulley m is made to revolve freely upon its shaft and is provided with a friction-clutch d^4 , which is operated by lever d^5 , pivoted upon arm l at e^2 . The balance-wheel e^3 , to which is attached a cam e^5 to operate a lever d^5 , also serves as a pulley to carry the belt e^4 , which revolves the pulley m . It will readily be seen that by this arrangement the folding apparatus will revolve only while the cam e^5 is in contact with the lever d^5 , the spring f^2 acting on and operating to disengage the friction-clutch from the pulley m when the cam e^5 disengages said 110 arm d^5 .

Bolted to the under side of the table c and extending backward or in opposite direction to the arms which hold the folding apparatus are arms $f^3 f^4$, provided with bearings to support the main driving-shaft f^5 , upon which is shown the crank h^2 and eccentrics h^3 and h^4 and also the pulley e^3 , by which means motion is applied to the operative parts of the machine. In the rearmost ends of these arms 120 are placed studs $h^5 h^6$, whose points enter the center holes in the ends of a shaft i' , which is designed to support a roll of paper.

To hold rolls of paper of different widths, so that it may be delivered centrally through 125 the machine, I place at opposite sides of the shaft i' racks $i^3 i^4$, which slide freely in dovetailed grooves $i^5 i^6$, with their teeth pointing inward and meshing with teeth in a pinion k' , which is placed in a mortise in the shaft 130 between the racks and revolves upon a pin k^2 . Attached to one end of each of these racks are collars $k^3 k^4$, which are adjustable upon the shaft. Thus when one collar is ad-

justed in either direction the other will be moved in the opposite direction in equal ratio, and the two collars will always be equally distant from the center of the shaft. When 5 the collars are placed properly against the ends of the roll, it will be centrally adjusted, and may be held in that position by one of the racks being pressed against the shaft by means of set-screws k^5 or k^6 , which attach the 10 collars to the racks. To put a roll of paper upon the shaft, one of the collars must be removed and then replaced, which is quickly and easily done after the shaft is removed from the machine.

15 Upon the table c are secured pillars l^1 l^2 l^3 l^4 , and on the tops of these are bolted curved plates l^5 and l^6 , lying parallel, or nearly so, and constituting a paper-guide. Between the plates l^5 l^6 , where the bolts pass through to 20 hold them, are thin washers to keep the plates apart, so that a sheet of paper may pass freely between them. The lower plate l^6 may be made in two parts with an open space between them, as shown in Fig. 3.

25 n^4 and n^5 represent shears (best shown in Figs. 2 and 3) for cutting off pieces of suitable length from the strip of paper to serve as a wrapper for the fruit. The upper blade n^4 of the shears is pivoted to the lower one at 30 n^6 . The blades n^4 n^5 are each preferably made of bars having thin cutting-blades attached to them. The actuating-rod p^9 is connected to the upper blade n^4 by a universal joint. This rod p^9 is loosely connected at its 35 lower end to one end of a fulcrum-lever l^8 , and to the other end of said lever l^8 a rod l^7 is connected, which is herein shown as moved by the eccentric h^3 . The lower blade n^5 of the shears is provided with lugs o^4 o^5 , which 40 extend downward and incline inward, presenting a dovetailed guideway, which receives and is adjustable on the table c . The lug o^4 is provided with a set-screw o^6 , by which the blade is held securely to the table at any 45 point desired.

Projecting from the vertical cylinder b is a lug p^4 , provided with a bolt p^5 , upon which the angular lever p^6 swings as a fulcrum. The upper end of this lever is turned laterally 50 inward toward the center of the machine, and on its end is secured the friction-clamp r^1 . This clamp is provided with an opening or slot r^2 to receive the end of the strip of paper after being passed from the roll and through 55 the open space between the curved guide-plates l^5 l^6 . The upper jaw r^3 of the clamp is provided with a pawl, which is made to turn freely upon pin r^4 . One arm r^5 of the pawl extends obliquely downward to the lower jaw 60 r^9 , upon which it will nip or clamp the paper. Another arm r^6 of the pawl extends obliquely upward and is provided in its extreme end with pin r^7 .

Projecting from the upper blade n^4 of the 65 shears is a lug s^2 , upon which is pivoted a device consisting of a leg s^3 and foot s^4 , the foot being set wholly on one side of the leg, as

shown in Figs. 2, 3, and 15, and bearing against the blade n^4 by gravity. The foot is hence permitted to move in but one direction. 70 When the clamp is moved in the direction in which it is to carry the paper, the pin r^7 in the arm r^6 will strike against the heel and cause the foot to swing in the direction of dotted line s^6 . When the pin has passed by the 75 foot, the latter will return to its normal position shown by gravity. When the clamp returns, the pin r^7 will slide over the inclined upper surface of the foot s^4 , moving the arm r^6 in the direction of the dotted line s^5 and 80 will cause the arm r^5 of the pawl to rise from the lower jaw r^9 of the clamp to allow the paper to enter. When the clamp has fully returned, the pin r^7 will be pressed down back of the foot by the spring s^8 , by which means 85 the paper will be clamped between the arm r^5 of the pawl and the lower jaw r^9 of the clamp.

A U-shaped spring s^7 is secured to the lower blade of the shears to support the paper above the blade of the shears to allow the lower jaw 90 r^9 of the clamp to pass under it. There should be several of these springs secured to the bar to keep the paper up, so that the clamp may pick it and carry it unobstructed from the blade of the shears. The lever p^6 is reciprocated by an eccentric-rod k^{10} , moved by the eccentric h^4 , and for adjusting the range of motion of said lever p^6 the eccentric-rod k^{10} is connected thereto at the slot p^{20} .

The table c , where the shears rest upon it, is 100 made crowning, as shown in Fig. 1, so that the shears wherever placed upon it and secured by the set-screw o^6 will line with the pivot or fulcrum p^5 , upon which the lever p^6 turns, and will be equidistant from it in order that the paper-feeding clamp r^1 may work 105 in harmony with the shears wherever they may be located upon the crowning portion of the table, and it is to assist and simplify such harmonious action that the foot s^4 is attached 110 to the shears.

The wrapper or severed sheet of paper should lie directly over the ring g , and in order to vary the size of said wrappers it will be necessary to change the throw of the lever 115 p^6 , so that it will operate to carry the paper forward a greater or less distance beyond the center of the ring, and also to adjust the shears so that they will operate to cut off the paper a greater or less distance from the center of the ring, such distances being necessarily equal.

To the vertically-sliding rod c' is secured a hub t^2 , which is connected by an arm t^3 to a hub t^4 , in which hub a rod t^5 is adjustably held 125 by means of a set-screw t^6 . The upward movement of the rod c' is so timed with relation to the paper-feeding clamp that it will at the upper limit of its stroke cause the end of the rod t^5 to meet a pin r^7 at a point indicated by 130 the dotted lines t^7 , and thus raise the arms r^5 r^6 of the pawl, thereby releasing the hold of the pawl upon the paper.

Upon the upper side and near one edge of

the curved plate t^5 is fixed a pillar t^8 . Upon the opposite edge of the plate is fixed an arm t^9 , which curves outwardly and upwardly. Upon the upper ends of this arm t^9 and pillar t^8 is supported an inclined guideway or trough u^2 , into which the fruit $u^3 u^4 u^5$, which is to be covered, is placed by hand or fed into it from a hopper or other receptacle.

A toothed wheel t , which is mounted centrally over the trough or guide u^2 , is employed to regulate the movement of the fruit $u^3 u^4 u^5$ through the trough, so that only one at a time will pass into the machine. The distance or space between the teeth of the tooth feed-wheel t will be made to correspond with the size of the article to be wrapped. The movement of the wheel is restrained by the friction-washer d^2 or otherwise. The rod c' is connected by a short link h^9 to the end of the lever a^4 , by which means it is made to slide vertically in bearings in arms $a' a^3$. The upper portion of the rod c' is turned inwardly until its end lies centrally over the combined folder and twister and enters a slot in the upper end of a pendant w^8 , which is joined or hinged to it by pin u^{12} , so that the pendant will swing upon the pin, as hereinafter shown. Also loosely mounted upon the pin u^{12} and located in a slot formed in the end of rod c' is a pawl d^3 , which is employed to move the feed-wheel t one tooth at a time. This pawl d^3 (shown separately in Fig. 16) has a flat face or portion, which bears against a like portion at the end of the slot in the rod c' , so that the said pawl will be held in its upright position. When the rod c' is moved upward, the pawl d^3 will come in contact with the tooth x' and turn the wheel. In the meantime the tooth x^2 will come in contact with the projection z upon the pendant w^8 , so that when the upper portion of rod c' arrives at its dotted-line position, Fig. 1, the pendant w^8 will be turned into the dotted-line position z^4 , thus allowing the fruit which has just been released by the turning of the feed-wheel to pass freely into the centering apparatus, which is placed at the front end and slightly below the trough u^2 and is attached to it by means of lug u and screw u' . The centering apparatus (see Fig. 7) consists of a broken ring or crescent-shaped piece u^6 and fingers $u^7 u^8 u^9 u^{10} u^{11}$, which swing freely upon pins $v' v^2 v^3 v^4 v^5$ and are pressed inwardly by springs, as shown in Fig. 8, or otherwise.

The bifurcated free end of a spring w^9 (see Fig. 4) rests on the flattened end of the pendant or plunger w^8 , which allows the pendant to be turned aside by the tooth x^2 and to assume a vertical position again when projection z is carried below the tooth. In Figs. 4^a and 4^b, the former being an end view of the latter, looking toward the right, it will be observed that the spring w^9 increases in thickness from the bifurcated end to the attached end. As the pendant or plunger continues to move downward it will come in contact with the fruit while in the centering appara-

tus and will carry said fruit down through the centering apparatus and also down through the combined folder and twister, carrying the paper with it, while the arms of said folder and twister wrap the paper about the fruit, leaving said fruit suspended by the nipping devices engaging the paper until removed by the hook a^2 .

As many merchants desire to have their name, initials, trade-mark, or other inscription printed upon the paper in which the fruit is wrapped, I have combined with this machine an apparatus whereby the paper may be printed or stamped in the center of the piece to be wrapped upon the fruit while it is passing from the roll into or through the machine. Pivoted near to one end of lever a^4 is a rod a^5 , which extends obliquely upward. In a socket at the upper end of this rod I secure the printing or stamping apparatus, (see Figs. 11, 12, 13, and 14,) which in this case consists of a vertical frame $a^6 a^7$, to the upper end of which is pivoted by pins $a^8 a^9$, passing through arms $z^5 z^6$, a plate z^7 , to which the type is secured in any suitable manner. In the open space between the two arms $a^6 a^7$ of the frame is placed a pad z^8 to supply the type with ink. The pad z^8 rests upon a plate z^9 , which is secured to a support z^{10} , projecting from frame or cylinder b^4 . The pad z^8 is provided at each side with a projection which slides freely in slots $b^8 b^9$ in the frame, so that when the frame is moved laterally the pad will follow and keep in adjustment with it. The rack-bar b^8 , by means of the slotted arm b^9 and bolt b^{10} , is adjustably secured to pillar d^6 , which projects upward from table c . Meshing into the teeth of this rack b^8 are the teeth of the gear-wheel d^7 . One portion of the wheel is extended to allow ample room for slot d^8 , in which pin d^9 will slide freely. The pin d^9 fits tightly in arms $e^6 e^7$, the object of the pin being to connect the type-plate z^7 with gear-wheel d^7 , so that the wheel and type-plate will simultaneously revolve upon the shaft e^8 . The object of the slot d^8 in the wheel and also the slots $e^9 e^{10}$ in arms $e^6 e^7$, which slide freely upon shaft e^8 , is to allow the type-plate z^7 to move toward or away from the center of the gear-wheel. Upon either side of the rack b^8 and parallel with it are guides $f^6 f^7$. The arms $e^6 e^7$ of the type-plate are pressed against these guides by a spring f^8 , secured to the column b and bearing against the rod a^5 . In the downward movement of the frame $a^6 a^7$ the type-plate will approach the wheel, as per dotted line x^3 , until pivots $a^8 a^9$ will be nearly in line with shaft e^8 , when pin d^9 will be at the bottom of slot d^8 . The gear-wheel will then commence to revolve upon its shaft e^8 and carry the type-plate in the direction of dotted line f^9 until the gear and plate will be in position of dotted lines $f^{10} f^{11}$, and the opposite edges of arms $e^6 e^7$ will bear against guides $f^6 f^7$. By still further downward movement of the frame the type will approach the inking-pad, as per dotted line f^{12} . By an upward

movement of the frame a^6 a^7 the type-plate and gear will return by the same path to their former positions, at which time the paper will be pressed against the curved plate b^5 and receive the impression from the type. The opening h^7 in the table and also the opening in the curved plate b^6 are large enough to allow all of these movements and to allow the apparatus to be so adjusted in relation to the shears that the imprint upon the paper when it has been moved forward will rest directly in line with the axis of the folding apparatus.

In order to insure the proper working of the parts, so that the imprint upon the paper shall be uniform and complete in whichever lateral position it may be desired to adjust the apparatus, the curves in the plate b^5 , arm b^9 , type-plate z^7 , and support z^9 should be made with reference to pivot h^{11} as a center. Of course the face of the inking-pad z^8 should be made the same curve as type-plate.

Before putting the machine in operation the fruit should be placed in the trough, as shown in the drawings, and the end of the paper upon roll i^2 should be passed between the curved plates b^5 b^6 and entered between the jaws r^3 and r^9 of the clamp r' . Then by applying power to the shaft f^5 the crank h^2 is turned, the rod h^8 moved longitudinally, and the lever a^4 , to which it is connected, is turned on its pivot h^{10} . The lever a^4 passes through slots, as k^8 , in the vertical cylinder b , and is connected with the rod c' by the link k^9 , so that as said lever is moved the rod c' rises vertically and its inwardly-turned end passes up through the centering device. In the meantime the type-plate z^7 has moved in the direction of the dotted lines x^3 f^9 f^{11} , Fig. 13, while eccentric h^4 , by means of rod k^{10} and angular lever p^6 p^6 , pivoted at p^5 , has caused the nipping device r' , with the end of the paper in its jaws, to move toward the folding and twisting device, the pin r^7 in the arm r^6 of the clamp r' moving away the foot s^4 in the direction of dotted line s^6 , and the eccentric or cam h^8 , by means of the rod l^7 and lever p^6 and rod l^7 , has caused the upper blade of the shears to move downward upon pivot n^6 . When the shaft f^5 has made one-half a revolution, the pin r^7 in the arm r^6 of the nipping device will have arrived at the point t^7 and have been raised to release the hold of the pawl upon the paper by rod t^6 , which, in the meantime has been carried upward by rod c' to the point t^7 , and the paper will have been severed by the shears ready to receive the fruit, and the toothed wheel t has been turned to allow the fruit to pass into the centering apparatus. In the meantime the type has been supplied with ink and has been raised from the inking-pad to a point indicated by dotted lines f^{11} , Fig. 13. While the shaft f^5 is making another one-half revolution, rod c' will be moved downward and the pendant w^8 will assume its vertical position and carry the fruit down through the centering apparatus, and with the paper

through the combined folder and twister, where it will be taken by the hook a^2 at its next uppermost movement, and the paper will be twisted upon it, as heretofore fully described. During this last-mentioned one-half revolution of the shaft f^5 the type has been moving upward in the direction of the dotted lines f^9 and x^8 , so as to press the paper against the curved plate b^5 to stamp or print it. In the meantime the upper blade of the shears n^4 has been raised, and the clamp r' has returned to its normal position, the pin r^7 in arm r^6 of the pawl passing over and upon foot s^4 , so as to raise arm r^5 of the pawl to allow the end of the paper to enter between the jaws of the clamp, and when pin r^7 is pressed down back of the foot s^4 by spring r^8 the arm r^5 of the pawl will press upon the paper and hold it tightly, ready to repeat the foregoing operation. Thus it will be seen that by one revolution of the driving-shaft the paper will be printed, carried forward, and cut into squares of suitable size, and the fruit will singly pass from the trough through the centering device and be carried with the paper through an apparatus for folding the paper around the fruit and the edges twisted to secure it to the fruit and will be dropped into an inclined guide w^4 to convey it away from the machine.

I claim—

1. In a machine for wrapping oranges and the like, a combined folder and twister comprising a series of contracting and expanding arms supported by a revolving ring, combined with a holder for engaging the wrapper next the article while the edges are yet held by the said folder and twister and holding it while said folder and twister rotates, substantially as described.

2. In a machine for wrapping oranges and the like, a contracting and expanding rotatable folder and twister, combined with a holder for engaging the wrapper next the article while the edges are yet held by the folder or twister, thereby holding the article against rotation while the twister operates, and a support for said holder, movable toward and from the folder and twister while the latter is operating to thereby insure twisting the gathered-in portion of the wrapper from a point next the article to the extreme edges of the wrapper, substantially as described.

3. In a machine for wrapping oranges and the like, a contracting and expanding rotatable folder and twister, combined with a holder for engaging the wrapper next the article while the edges are yet held by the folder and twister and for holding it while the said folder and twister rotates, substantially as described.

4. In a machine for wrapping oranges and the like, a combined folder and twister for folding the wrapper about the article and twisting its edges, combined with a holder for engaging the wrapper next the article while the edges are yet held by the folder and twister, and a support for the holder, movable toward and from the folder and twister, whereby the

wrapped article may be removed from its engagement with the said folder and twister, substantially as described.

5. In a machine for wrapping oranges and the like, a combined folder and twister comprising a series of automatically-movable arms having nipping devices at their ends for engaging and holding the gathered-in edges of the wrapper, and a rotatable ring to which said arms are connected, over which the wrapper is placed, and down through which it is carried by the orange as the latter descends, substantially as described.

6. In a machine for wrapping oranges and the like, a combined folder and twister consisting of a series of automatically-movable arms borne by an intermittently-rotatable ring, combined with a holder for engaging the wrapper next the article while the edges are yet held by the folder and twister, and thereby holding the article against rotation while the ring revolves, substantially as described.

7. In a machine for wrapping oranges and the like, a combined folder and twister consisting of a series of automatically-movable arms borne by an intermittently-rotatable ring, combined with a holder for engaging the wrapper next the article while the edges are yet held by the folder and twister, and thereby holding the article against rotation while the ring revolves, and a support for the holder, movable toward and from the folder and twister, whereby the wrapped article may be removed from its engagement with said arms, substantially as described.

8. In a machine for wrapping oranges and the like, a combined folder and twister comprising a series of automatically-movable arms having nipping devices at their ends for engaging and holding the gathered-in edges of the wrapper, a rotatable ring to which said arms are connected, over which the wrapper is placed, and down through which it is carried by the orange as the latter descends, combined with a holder for engaging the gathered-in portion of the wrapper next the article while the edges are yet held by the nipping devices of the folder and twister and means for moving the holder away from the folder and twister while the latter is rotating, substantially as described.

9. In a machine for wrapping oranges and the like, a combined folder and twister comprising a series of automatically-movable arms having nipping devices at their ends for engaging and holding the gathered-in edges of the wrapper and another series of automatically-movable arms arranged alternately with relation to the first-named series, combined with a rotatable ring to which all of said arms are connected, over which the wrapper is placed, and down through which it is carried with the orange as the latter descends, and a holder for engaging the wrapper next the article while the edges are held by the nipping devices to thereby hold the article against rotation while the ring revolves, substantially as described.

10. In a machine for wrapping oranges and the like, a combined folder and twister comprising a series of automatically-movable arms formed at their lower ends to present nipping devices, combined with a forked holder for engaging the wrapper between the articles and the nipping devices, substantially as described.

11. In a machine for wrapping oranges and the like, a folder and twister, combined with a holder and a feeding device for feeding the articles one at a time and means for forcing them down through the folder and twister, substantially as described.

12. In a machine for wrapping oranges and the like, a feeding device consisting of a feed-trough, a feed-wheel, a pawl for rotating said feed-wheel intermittently, a pawl-carrier, and a pendant borne by said pawl-carrier for assisting the progress of the article, substantially as described.

13. In a machine for wrapping oranges and the like, a combined folding and twisting device and a centering device located above it, combined with a feeding-trough, a feeding device for feeding the articles one by one, and a plunger for forcing the article down through the centering device, substantially as described.

14. In a machine for wrapping oranges and the like, wrapping devices, combined with a centering device consisting of a series of automatically-movable arms, a ring to which they are attached, broken out to provide a passage at one side of it, a feeding device for feeding the articles one at a time, and a plunger for forcing the article down through the centering device, substantially as described.

15. In a machine for wrapping oranges and the like, a folder and twister, combined with a feed-trough, toothed feeding-wheel, vertically-movable rod for moving said feed-wheel step by step, a centering device in line with the folder and twister, and means operated by said vertically-movable rod for forcing the article down through the centering device and combined folder and twister, substantially as described.

16. In a machine for wrapping oranges and the like, a contracting and expanding rotatable folding and twisting device, a centering device located above it, and a plunger for forcing the orange down through the centering device, combined with a paper-feeding mechanism for feeding forward a strip of paper while the orange is held by the centering device and a paper-cutter for cutting off the strip, substantially as described.

17. In a machine for wrapping oranges and the like, a combined folder and twister comprising two pairs of automatically-movable arms and a wing on the end of each arm, arranged to form a square, as shown, one pair of said wings being arranged obliquely with

relation to the other pair, substantially as described.

18. In a machine for wrapping oranges and the like, wrapping devices, combined with a paper-feeding mechanism and adjustable cutting-off mechanism consisting of two blades movable one with relation to the other and U-shaped springs secured to the under blade and adapted to direct the paper over said blade, substantially as described.

19. In a machine for wrapping oranges and the like, wrapping devices, combined with nipping devices to engage the end of a strip of paper, a pivoted support therefor, whereby the paper is fed in the arc of a circle, means for reciprocating said support, and a paper-cutter adjustable in the arc of a circle of which the pivot of the support for the nipping devices is the center, substantially as described.

20. In a machine for wrapping oranges and the like, wrapping devices, combined with reciprocating nipping devices to engage the end of a strip of paper and feed it forward and means for adjusting said nipping devices to vary their range of motion, an adjustable paper-cutter comprising two blades, and an actuating-rod for it, connected with the movable blade by a universal joint, substantially as described.

21. In a machine for wrapping oranges and the like, wrapping devices, combined with a shaft to support a roll of paper, two collars on said shaft to hold the roll of paper centrally with relation to the shaft, and connecting means between said collars, whereby one will automatically move the other in the opposite direction, substantially as described.

22. In a machine for wrapping oranges and the like, wrapping devices, combined with paper-feeding mechanism, a paper-guide consisting of two stationary plates $l^5 l^6$, the former presenting an impression-surface and the latter supporting the paper and having an opening through it, a printing device adapted to impress the paper through said opening in the plate l^6 , and cutting-off mechanism for

severing the strip to thereby form separate printed wrappers, which are wrapped about the articles by the aforesaid wrapping devices, substantially as described.

50

23. In a machine for wrapping oranges and the like, wrapping devices, combined with a paper-guide consisting of two plates $l^5 l^6$, the former presenting an impression-surface and the latter supporting the paper and having an opening through it for the type-plate, and a paper-printing device consisting of an inking-pad and an invertible type-carrying plate to receive the ink and thereafter print the paper, substantially as described.

60

24. In a machine for wrapping oranges and the like, wrapping devices, combined with a paper-guide consisting of the plates $l^5 l^6$ and a paper-printing device consisting of an adjustable inking-pad, a type-carrying plate, a toothed sector for inverting said plate, and an adjustable rack, and means for keeping the sector in mesh with the rack, substantially as described.

65

25. In a machine for wrapping oranges and the like, wrapping devices and a paper-guide, combined with a vertically-sliding printing device, a guide $f^6 f^7$ therefor, and spring for holding the printing device in contact with said guide, substantially as described.

75

26. In a machine for wrapping oranges and the like, wrapping devices, combined with a reciprocating paper-feeding device, consisting of a nipping device, a foot, as s^4 , for opening it to receive the paper, and shears for cutting off the paper, to which said foot is attached, and means for adjusting said shears, and thereby adjusting the foot, substantially as described.

In testimony whereof I have signed my name to this specification in the presence of two subscribing witnesses.

SETH D. TRIPP.
